UNITED STATES PATENT OFFICE.

CHARLES W. ARMBRUST, OF CRYSTAL LAKE, ILLINOIS, ASSIGNOR OF ONE-FOURTH TO
SYDNEY STEIN, OF CHICAGO, ILLINOIS.

BRAKE-SHOE.

1,014,933.

Specification of Letters Patent.

Patented Jan. 16, 1912.

Original application filed December 22, 1910, Serial No. 598,700. Divided and this application filed May 27, 1911. Serial No. 629,880.

To all whom it may concern:

Be it known that I, CHARLES W. ARMBRUST, a citizen of the United States, residing at Crystal Lake, in the county of McHenry and State of Illinois, have invented 5 certain new and useful Improvements in Brake-Shoes, of which the following is a specification.

This invention relates to brake-shoes having reference mainly, although not exclusively, to shoes of the type known as "interlocking" shoes wherein the back and face of the shoe are provided with interlocking means whereby a partially worn shoe can 10 be detached from the head and applied to the wearing face of a new shoe so that the partially worn shoe is completely used up.

My present invention, which constitutes a division of an application heretofore filed 20 by me on the 22d day of December, 1910, Serial No. 598,700, relates mainly to the feature of a detachable central fastening lug through which passes the usual locking-pin or key, by the use of which the thickness of 25 the shoe may be somewhat reduced and its strength or power of resistance to transverse breaking strains increased.

My invention and its manner of use will be readily understood when considered in 30 connection with the accompanying drawings showing preferred forms thereof, in which—

Figure 1 is a side elevation, partly in section, of a shoe employing one form of detachable malleable central fastening lug. 35 Fig. 2 is a view similar to Fig. 1, but showing another form of detachable central lug adapted to fit a recess or socket in the spacing lug or plate and the back of the shoe. Fig. 3 is a cross-section on the line 3—3 40 of Fig. 1. Fig. 4 is an end elevation partly in broken section of the structure shown in Fig. 2. Fig. 5 is a detail fragmentary top plan view of the central fastening lug shown in Figs. 2 and 4, and the portion of the spacing lug or plate and the back of the shoe 45 which cooperates therewith. Fig. 6 is an end elevation of the structure shown in Fig. 1.

Referring to the drawing, 10 designates 50 the main body of the shoe, on the back of which and approximately coextensive both longitudinally and laterally thereof is what I term a spacing-lug or plate 11, preferably cast integral with the shoe-body 10. Upon

and integral with the end portions of the 55 spacing-lug 11 are formed end lugs 14 beveled or undercut on their lower sides to interlock with correspondingly shaped recesses 15 formed in the face of the shoe near its ends. The recesses 15 are open on one side 60 of the shoe but preferably closed on the opposite side by the opposite wall of the shoe to prevent separation of the two shoes on that side through which the open ends of the recesses 15 are formed, the latter side 65 of the shoe being that designed to lie adjacent to the flange of the car wheel.

Referring to Figs. 1, 3, and 6, 19 designates a short transversely dovetailed integral lug formed on the back of the spacing-lug 11, and 20 designates a correspondingly shaped transverse recess or socket formed centrally of the face of the shoe-body. Co-operating with the lug 19 is a malleable locking-lug 21 having a key-way 22 formed 70 therethrough, and, in its base, a dovetailed transverse slot 23 adapted to have a sliding and interlocking fit with the lug 19, as clearly shown in Figs. 1 and 3.

In the modified form of the invention 80 shown in Figs. 2, 4, and 5, the central locking-lug 24 is provided with the usual key-way 25 and has a tapered or outwardly flared base 26 that engages an undercut socket 27 formed in the spacing-lug 11 and 85 shoe-body 10. To provide for the insertion of the lug 24 in the socket 27, one end of the latter communicates with a shallow socket or entrance-way 28 formed opposite one end of the main socket 27, the entrance-way 28 90 being of the full width of the base 26 of the lug, so that the latter can be set in the entrance-way 28 and then slid down into interlocking engagement with the undercut walls of the main socket 27. The chief advantages of these central fastening lugs formed independently of the brake-shoe body and detachably keyed to the back of the latter reside in the fact that when a partially worn shoe is to be applied to a 100 new shoe, this central fastening lug can be removed, consequently making it unnecessary to socket the central part of the face of the shoe at all or more than enough to accommodate the short lug 19, thus permitting the use of a thinner shoe and the attainment of greater transverse strength in the shoe.

It will be evident to those skilled in the art that slight changes and variations in the forms and dimensions of the parts herein shown and described can be made without involving any difference in principle of operation or the manner of action and manipulation. Hence, I regard such minor changes and variations as within the scope of the invention as defined in the appended 10 claims.

I claim:

1. A brake-shoe comprising a body-member, an independently formed fastening lug, and means for detachably keying the latter 15 on the back of said body-member, substantially as described.
2. A brake-shoe comprising a body-member and a detachable fastening lug therefor, said body-member and fastening lug being

provided with interfitting parts whereby 20 said fastening lug may be secured to and removed from said body-member by a relative sliding movement therebetween, substantially as described.

3. A brake-shoe comprising a body-member 25 and a detachable fastening lug therefor, said body-member and detachable fastening lug being provided one with a dovetailed member and the other with a dovetailed recess adapted to be slidingly engaged by 30 said dovetailed member in applying and removing said fastening lug, substantially as described.

CHARLES W. ARMBRUST.
